(51) **LOC (13) Cl.** 14-04

CLAIM

(52) **U.S. Cl.**

The ornamental design for a display screen or portion
thereof with graphical user interface, as shown and
described.

USPC **D14/485**

DESCRIPTION

(58) **Field of Classification Search**

The file of this patent contains at least one drawing/photograph
executed in color. Copies of this patent with color
drawing(s)/photograph(s) will be provided by the Office
upon request and payment of the necessary fee.

USPC D14/485-495

The sole FIGURE shows a display screen or portion thereof
with graphical user interface showing our new design.

CPC G06F 3/048; G06F 3/0481; G06F 3/04812;

The peripheral dashed broken lines illustrate a display
screen or portion thereof, and form no part of the claimed
design.
